HEATER CONSTRUCTION

Walter M. Cross, Kansas City, Mo., assignor to
 Babcock & Wilcox Co., New York, N. Y., a corporation of New Jersey

Application February 16, 1925, Serial No. 9,554
 Renewed January 29, 1932

7 Claims. (Cl. 122—276)

This invention has reference to fluid heaters of the drumless type, in which the fluid enters as a liquid at one end of a long conduit and emerges as vapor.

5 One of the salient features of the invention is the provision of a generator of the aforesaid character which is differentiated from the so-called "flash" or "semi-flash" boiler in that the fluid extends as a liquid through the larger portion of the entire conduit, or conduits in parallel, and receives pre-heating in the cooler gas zone, then enters a vaporizing section in the hottest gas zone, from which it enters a superheating section at a gas zone of intermediate temperature with the conduits thereof protected by the location of the vaporizing section.

A further feature is an arrangement such that the fluid medium may be utilized in successive stages of expansion to saturation and returned to the superheating section in the location above described for the superheater for the addition of heat.

An additional object resides in the arrangement of the sections of the conduits in such form that there is freedom for expansion, and provision for cleaning the interior of the conduit sections.

In the drawings—

Fig. 1 is a plan view of a generator constructed in accordance with the present invention, but with the insulated top and horizontal baffle removed to disclose the tube arrangements;

Fig. 2 is a transverse, vertical sectional view taken through the central portion of the heater shown in Fig. 1.

Fig. 3 is a diagrammatic view showing the continuity of the path of the fluid from liquid entrance to final outlet;

Fig. 4 is a fragmentary front elevation, in section of the header, of one side of the tube banks; and

Fig. 5 is a fragmentary sectional view along the line 5—5 of Fig. 4.

In detail—

45 The heater consists essentially of a heavily insulated horse-shoe shaped chamber in which there is centrally positioned, at the lower portion thereof, heating elements 2 consisting of a tunnel-shaped member preferably constructed of carborundum brick or other material adapted to withstand very high temperatures, and which is suitably located so that the gases spread out in the manner hereinafter described.

55 This heating element 2 may be of any type other than that herein described, but in the

present instance it is shown, for the purposes of illustration only, as an internally fired tunnel for use with gas or oil, heat being radiated from all sides thereof excepting the bottom.

Ports or openings are provided at the top of 60 this tunnel-shaped heater member through which the gases have their exit. Air may be supplied to the burner along with the gas if desired, or a separate fuel supply may be used, but, if desirable, dependent upon conditions, the 65 supply of air, the supply of combustible and air, or the supply of combustible alone may be furnished through a pipe 3 incorporating a pre-heater 4 located in path of the exit gases from the furnace, and which pipe is continued to the 70 heating means 2.

The preheater 4, in the form shown, consists of a group of tubes extending between two flanges, but such form of preheater is shown merely for the purpose of illustration of a type 75 which may be used.

The chamber 1, which is closed at the top except for the outlet 5 to the flue, and in which the preheater 4 is disposed, comprises a horizontal baffle 11 near the top and through which are 80 peripheral ports 12, as indicated in Fig. 2. Beneath this baffle and above the source of heat 2, are groups of curved tubes forming a conduit, and which is divided into three sections, namely, an outer preheating section constituting five 85 lateral rows, an inner vaporizing section at the center constituted of two rows, and an intermediate superheating section, as shown.

It is to be noted that the connections between the ends of adjacent lines are practically in the 90 form of return bends as indicated in Figs. 4 and 5, but with the headers provided with plugs 28 opposite the end of each section which may be removed for the purpose of cleaning the tubes. The connections between the ends of adjacent 95 tubes are made at one side of the chamber and the tube ends at the opposite side, designated diagrammatically in Fig. 1 as 25, are merely return bends which cause the liquid to loop back through the next successive tube through which the liquid is passing, the tube ends being connected up in such a manner that a continuous passage is effected from the inlet to the outlet of the boiler.

100 It will be noted that there is provided what might be termed a "once through" boiler which has a multiplicity of parallel sections serially connected and of U-shape form so that expansion and contraction are readily taken care of, the 110

plugs 28 in the headers being adequate for cleaning of the tube sections.

It is also to be noted that the water is pre-heated at the cooler gas end, then progresses 5 towards the center of the furnace where it is vaporized at the hottest gas zone, from which it finally goes to the zone between the preheating and vaporizing sections where it receives super-heat in the superheater which is protected by the 10 vaporizing tubes, as shown.

In connection with Fig. 3 there is shown the water entering at 13, passing through the serially arranged preheating conduits 6 through which the fluid advances from the outer or cooler portions 15 of the heating chamber inwardly towards the hotter portion thereof, and then through pipe 14 to the vaporizing tubes 7, from which it travels through pipe 15 to the first stage of super-heating 8. From this it leaves through the pipe 20 16 to the expansion stage 17, from which it is returned through the pipe 18 to a second stage superheater 9, leaving this superheater through the connection 19 to a second expansion stage 20, from which it returns through the pipe 21 and is 25 received and passed through the third stage superheater 10, from which it emerges through the pipe 22 to a third expansion stage 23, the condensate being recovered by the condenser 24.

In practicing the invention it is understood 30 that the generator is preferably operated at approximately 1,500 pounds pressure, and the fluid maintained liquid throughout the major portion of the continuous conduit represented by the sectional views described, and hence no appreciable 35 amount of evaporation occurs until the vaporizing tubes have been reached by the liquid, but that the liquid is completely converted into vapor before it reaches the superheating surface hereinbefore described.

40 As described in connection with Fig. 3, the original 1,500 pounds pressure may be reduced through an expansion stage, such as a turbine or the like, to 1,000 pounds, such expansion stage being diagrammatically indicated in Fig. 45 3 at 17, and from which it is then returned to the second stage superheater 9 which, in practice, may be positioned adjacent the superheater 8, and from which it is then led to the expansion stage 20 and back to a third stage superheater 50 indicated at 10 and similarly positioned with respect to the general assembly.

The final stage of expansion 23 may exhaust to a condenser 24, or the like.

It is to be noted that plugs 28 closing openings 55 27, functioning as return bends for the tubes, also provide access by means of which a flexible cleaning element may be used to relieve the tubes of any scale or other material.

While in the foregoing there has been described 60 preferred forms which the invention assumes in practice, it is nevertheless to be understood that other modifications may be provided dependent upon conditions under which the invention is to be used, and a number of conduits may be arranged in parallel with each having a serial flow path.

I claim:

1. A heater of the character described, consisting of an insulated combustion chamber, a source of heat therein, a plurality of banks of U-tubes positioned about the heating means in semi-circle arrangement and connected to produce a continuous travel of the heating medium therethrough, a flue in the upper portion of the combustion 70 chamber, an upper horizontally positioned baffle 75

positioned to direct the combustion gases over the tubes in their travel to the flue.

2. A heater of the character described, consisting of an insulated combustion chamber, a source of heat therein, a plurality of banks of U-tubes horizontally positioned about the heating means in a semi-circle arrangement and connected to produce a continuous travel of the medium therethrough, said tubes comprising a preheating stage, a vaporizing stage and a plurality of super-heating stages, the outer tubes of the semi-circle comprising the preheating stage, the inner tubes the vaporizing stage and the intermediate tubes vertically separated into three stages of superheat, and a flue in the upper portion of the combustion chamber for carrying off the spent gases. 80 85 90

3. A heater of the character described, comprising a combustion chamber having a source of heat in the lower central portion thereof, a plurality of banks of U-tubes positioned about the heating means in semi-circular arrangement, the said banks of tubes connected to produce a continuous flow of the circulating medium, the outer banks of tubes, or those furthest from the heat source, comprising a preheating stage, the 100 inner banks of tubes a vaporizing stage and the intermediate banks stages of superheat, and a flue in the upper portion of the combustion chamber for discharging the spent combustion gases. 95 100 105

4. A heater of the character described, comprising a combustion chamber having a source of heat in the lower central portion thereof, a plurality of banks of U-tubes positioned about the heating means in semi-circular arrangement, the said banks of tubes connected to produce a continuous flow of the circulating medium, the outer banks of tubes, or those furthest from the heat source, comprising a preheating stage, the inner banks of tubes a vaporizing stage and the intermediate banks stages of superheat, a flue in the 110 115 upper portion of the combustion chamber for carrying off the spent gases.

5. A heater of the character described comprising a combustion chamber, a source of heat therein, a plurality of banks of U-tubes positioned about said source of heat in a semi-circular arrangement, said source of heat being intermediate the ends of the tubes and arranged to supply heat by radiant energy and by convection over the tube surfaces, the said banks of tubes connected to produce a continuous flow of the circulating medium, said banks being connected in vertical rows to pass the circulating medium through the bank of tubes farthest from the heat source, thence through the bank of tubes closest to the 120 125 heat source and finally through the bank of tubes intermediate the two last mentioned banks, and a flue in the upper portion of the chamber for discharging the spent gases.

6. A heater including a casing and a centrally disposed fire, bent tubes arranged with the path of the heating gases from the center crossing the tubes toward the casing and out, said tubes serially connected and arranged in groups with reference to the flow of heated gases, a feed pump 135 water supply delivering water to that one of said groups of tubes which is located in the coolest gas zone and through which it flows, to the second of said groups located in the hottest zone 140 145 supplying said second group with heated water, and a connection from said second group to a third group located in the zone of intermediate gas temperature whereby the steam generated in the second group becomes superheated in the 150

third group, and an outlet from the last group to a point of use.

7. A heater including a casing and centrally disposed fire, bent tubes arranged with the path 5 of the heating gases from the center crossing the tubes toward the casing and out, said tubes serially connected and arranged in groups with reference to the flow of heated gases, a feed pump water supply delivering water to that one of said 10 groups of tubes which is located in the coolest gas zone and through which it flows to the second of said groups located in the hottest zone supplying said second group with heated water, and a connection from said second group to a third group located in the zone of intermediate gas temperature whereby the steam generated in the second group becomes superheated in the third group, an outlet from the last group to a point of use, and returning the steam from the point of use to an additional group for reheating in an intermediate gas temperature zone. 80 85
